United States Patent Office.

G. C. BROWN, OF ATLANTA, GEORGIA.

Letters Patent No. 101,091, dated March 22, 1870.

IMPROVEMENT IN CHURNS.

The Schedule referred to in these Letters Patent and making part of the same.

To all whom it may concern :

Be it known that I, G. C. BROWN, of Atlanta in the county of Fulton and in the State of Georgia, have invented certain new and useful Improvement in Churns; and do hereby declare that the following is a full, clear, and exact description thereof, reference being had to the accompanying drawings and to the letters of reference marked thereon making a part of this specification.

The nature of my invention consists in the construction and general arrangement of a "churn," as will be hereinafter fully set forth.

In order to enable others skilled in the art to which my invention appertains to make and use the same, I will now proceed to describe its construction and operation, referring to the annexed drawings, in which—

Figure 1 is a plan view of the rod of the churn; Figure 2 is a vertical section of the entire churn; and

Figure 3 is a perspective of the same.

Figure 4 is a horizontal section of the dasher.

A represents the churn, made round, and tapering upward, so as to be narrower at the top than at the bottom.

In the center of the bottom of the churn A is a small socket or bearing, a, for the insertion of the lower end of the vertical shaft B, which passes upward through a tube, b, in the center of the lid e, said tube forming the upper bearing for the shaft.

Near the lower end, on the shaft B, is secured a circular plate, D, and at a suitable point on the said shaft above the circular plate is secured a cross formed of horizontal V-shaped bars E E, which are connected with the plate D by means of vertical bars d d, said bars being either round, flat, or square.

Between the series of bars d d the plate D is perforated with a round hole, as shown in fig. 4. The perforated circular plate D, vertical bars d d, and horizontal V-shaped bars E E form the churn-dasher.

Above the bars E, on the shaft B, is secured the fly G, which is formed of a circular plate with wings curved upward, for a purpose that will be hereinafter set forth.

Upon the upper side of the lid C is the curved frame H, through the center of which is passed a small shaft or journal, e, having at its lower end a cap or socket, f, which fits upon the upper end of the dasher-shaft

B, and is so constructed that if said shaft or journal e is revolved, the shaft B will also be turned.

At the upper end of the journal e, above the frame H, is a pinion, I, which gears with a cog-wheel J, the journal or bearing of which is placed on the frame H, as seen in fig. 2.

From the upper side of the frame H, surrounding the pinion I, is another frame, K, which supports and forms the bearing for a wheel, L. This wheel is provided with cogs on its inner periphery, and is so constructed that its periphery is down below the center, so that the cogs can gear with the cog-wheel J, and thus, when the wheel is turned by the crank M, the necessary rotary motion is communicated to the churn-dasher.

In the lid or cover C is a tube, N, covered with a suitable cap.

The butter that flies up around the inside of the churn above the milk is washed down by pouring water through the tube N in the cover. This water passes onto the fly G, and is by the fly thrown all round the inside of the churn while the dasher is in motion, and washes down all small particles of butter. This saves time and trouble of detaching the cover for that purpose.

The butter is gathered on the dasher, as fast as it is made, by the dasher running one way only.

Having thus fully described my invention,

What I claim as new, and desire to secure by Letters Patent, is—

1. The combination and arrangement of the shaft B, perforated plate D, vertical bars d d, horizontal bars E E, and fly G, all substantially as and for the purposes herein set forth.

2. The arrangement of the frames H K, wheels L J, crank M, and pinion I, all substantially as shown and described.

3. The combination and arrangement of the churn A, dasher B D d E, fly G, cover C, tube N, journal e, cap f, pinion I, wheels J L, and crank M, all constructed as described, to operate substantially in the manner and for the purpose herein set forth.

In testimony that I claim the foregoing, I have hereunto set my hand this 23d day of October, 1869.

Witnesses:

G. C. BROWN.
